UNITED STATES PATENT OFFICE.

MARY E. HEINRICH, OF FREEPORT, NEW YORK.

DESIGN FOR A SPORT SUIT.

Application filed October 11, 1921. Serial No. 507,150. Term of patent 7 years.

To all whom it may concern:

Be it known that I, MARY E. HEINRICH, a citizen of the United States, residing at Freeport, in the county of Nassau and State of New York, have invented a certain new, original, and ornamental Design for a Sport Suit, of which the following is a specification, reference being had to the accompanying drawing, forming part thereof.

In the drawings, Fig. 1 is a front view and Fig. 2 is a rear view of a sport suit, showing my new design.

I claim:

The ornamental design for a sport suit, as shown.

MARY E. HEINRICH.
